RADIO ANTENNA

Henry (Heinie) L. Johnson, Bloomington, Ill.

Application February 18, 1937, Serial No. 126,391

5 Claims. (Cl. 250—33)

This invention relates to radio antenna for use with all radios.

The object of the invention is to provide a highly effective antenna that is convenient in size and weight for permanent trouble-free installation for ordinary home use.

A further object is to provide an antenna of higher efficiency than the conventional aerial wires now in use.

10 And a still further object is to provide a multiple wire antenna variable by selective circuits for variable antenna usage.

Other objects and benefits will be disclosed by the following drawing and specification in which:

15 Fig. 1 is a broken isometric view of my antenna;

Fig. 2 is an enlarged broken sectional view of the antenna wire proper showing the smaller wire embedded in the larger and the knurled 20 surface;

Fig. 3 is an enlarged right angle cross section of the two antenna wires as they are fit together in the spirally formed groove in the larger wire;

Fig. 4 is a view similar to Fig. 3 after the two 25 wires have been locked together in the spiral groove by a knurling or roughening operation; and

Fig. 5 is a diagrammatic view showing a variation of the antenna circuits to be described later.

30 Now referring to the illustrations, the same part is designated by the same reference numeral wherever it occurs throughout the several views.

The numeral 10 designates the large wire which is of light metal into which a spiral groove has 35 been milled. In the preferred embodiment of

my invention, I use a one-quarter inch diameter aluminum wire. The numeral 11 is a smaller wire of different radio frequency conductor characteristics. I prefer to use copper for this smaller

40 wire and to obtain variations in results I make this wire either shorter or longer than the larger aluminum wire, insulate it from the larger wire and/or cover the smaller wire with nickel, tin, silver, lead or other metals of different electrical

45 conductivity. As a "trial and error" experimenter with radio antennas, I have discovered that such variations as above give variable results and altho I do not know the absolute scientific reasons, the results have been quite successful.

50 The numeral 12 designates a conventional form of end clip attached to the antenna by bolts 13. A suitable ring 14 connects the clips 12 to conventional insulators 15 and the feeder wire 16 leads to the antenna post on the radio receiver.

Referring to Fig. 3, the spiral groove 17 is shown with the small wire 11 inserted therein. In Fig. 4 I show how the lips of the groove 17 have been inverted over the wire 11 by the knurls 19 securely sealing the wire 11 in the spiral groove. 5

The knurling 19 is of a form to greatly increase the surface area of the antenna wire by covering the surface with innumerable projections and pits.

10 In Fig. 5 I have indicated by diagram means by which I make a non-tuneable double antenna wherein the two circuits, using wires 11 and 11', are insulated apart but built into a single wire giving a general purpose all-wave antenna, wherein, by special coupling, eight different antenna combinations are available.

Many variations of this same idea are, of course, possible and I illustrate this example only to disclose the scheme.

20 To explain the advantages of my antenna and its structure, I desire to explain that because of the large diameter of the wire and its greatly increased surface area, I can get effective results with a relatively short length of wire. This short length of large diameter wire is both light and 25 stiff, and, as a result, it may be mounted in a small space and held rigidly and permanently in position. It will be appreciated that my mounting of the small wire in the larger is a rigid construction that will inhibit extraneous noises. 30 Further, that the knurled or expanded surface of the larger wire and spiral winding of the smaller wire provides a multi-directional structure 35 distinctively different from the conventional aerial wire.

By using bare wires, I produce a dual metal, dual surface aerial combining electrical and structural advantage of both wires in a single antenna; by insulating the wires from each other I obtain a multiple aerial in a single wire. 40

In the foregoing I have disclosed what I now consider to be the preferred embodiment of my invention. However, as I have indicated, numerous optional structures are possible and I do not desire to be limited to the structure shown except as by the appended claims.

I now claim as new:

1. In a radio antenna, a radio frequency collector wire of aluminum alloy, a spiral groove in said collector wire, and an insulated copper conductor wire extending from one end of said groove to a point short of the full length thereof, said collector and conductor having approximately 50 1.6 micro-micro farad capacity per inch.

2. In a radio antenna, a radio frequency col- 55

lector wire of aluminum alloy, a knurled surface on said wire, a spiral groove in said collector wire, and an insulated copper conductor wire extending from one end of said groove to a point short 5 of the full length thereof, said collector and conductor having approximately 1.6 micro-micro farad capacity per inch.

3. In a radio antenna, a radio frequency collector wire of aluminum alloy approximately 20' 10 in length, a knurled surface on said wire to increase wire surface area projecting in all directions, a spiral groove in said collector and an insulated copper conductor wire extending from one end of said groove three or more feet in 15 said collector wire, whereby said conductor wire is shorter than the collector wire to provide variable transmission capacity in the antenna.

4. In a radio antenna, a radio frequency collector wire of aluminum alloy approximately $\frac{1}{4}$ " in diameter and 20' in length, a knurled surface on said wire to increase wire surface area projecting in all directions, a spiral groove in said 5 collector, and an insulated copper conductor wire of approximately 20 gauge, extending about 13' 7" in said groove of the collector wire whereby radio frequency impulses from 600 to 60,000 kilocycles are received and transmitted. 10

5. A radio antenna generally as described in claim 4, having the same proportionate wire capacities whereby radio frequency impulses from 600 to 60,000 kilocycles are received and transmitted. 15

HENRY (HEINIE) L. JOHNSON.
